[57] CLAIM

The ornamental design for a cabinet for an input-output device, substantially as shown and described.

DESCRIPTION

FIG. 1 is a perspective view of a cabinet for an input-output device, showing my new design;

FIG. 2 is a top plan view;

FIG. 3 is a front elevational view;

FIG. 4 is a rear elevational view; and

FIGS. 5 and 6 are side elevational views.

The broken line showing is for illustrative purposes only and forms no part of the claimed design.

FIG.1.

FIG.2.

FIG.3.

FIG.4.

FIG.5.

FIG.6.
